United States Patent Office

Des. 179,413
Patented Dec. 18, 1956

179,413

FLOWER TRELLIS

Carmen D'Amico, St. Louis, Mo.

Application January 3, 1956, Serial No. 39,579

Term of patent 14 years

(Cl. D35—3)

Fig. 1 is a perspective view of a flower trellis showing my new design;

Fig. 2 is a front elevational view of the design; and Fig. 3 is a side elevational view of the design.

I claim:

The ornamental design for a flower trellis, substantially as shown.
